UNITED STATES PATENT OFFICE.

SVEN T. NELSON, OF MICHIGAN CITY, INDIANA, ASSIGNOR TO SULLIVAN MACHINERY COMPANY, A CORPORATION OF MASSACHUSETTS.

TEMPERING MECHANISM.

Application filed November 8, 1923. Serial No. 673,450.

To all whom it may concern:

Be it known that I, SVEN T. NELSON, a citizen of the United States, residing at Michigan City, in the county of Laporte and State of Indiana, have invented certain new and useful Improvements in Tempering Mechanism, of which the following is a full, clear, and exact specification.

My invention relates to tempering mechanism, and more particularly to an improved tempering mechanism for mining machine cutter bits.

It has for an object to provide an improved tempering mechanism for such bits, whereby, as distinguished from subjecting the entire bit to the tempering bath as heretofore, it is made possible to temper only the working or cutting end of said bit. A further object of my improved mechanism is to provide improved means for supporting the bits during tempering and discharging the same after passage through the tempering bath. Other objects and advantages of my invention will hereinafter more fully appear.

In the accompanying drawings I have shown for purposes of illustration one form which my invention may assume in practice.

In these drawings,—

Fig. 1 is a diagrammatic side elevation, partially in longitudinal section, of my improved mechanism, showing a furnace arranged adjacent the same.

Fig. 2 is a vertical section taken substantially on line 2—2 of Fig. 1.

Fig. 3 is a detail plan view of a portion of the bit conveyor, showing the bit carrying means thereon.

Fig. 4 is a transverse section of the bit conveyor shown in Fig. 2, showing a bit disposed in position thereon.

In this illustrative construction, I have shown my tempering mechanism used in connection with a bit heating furnace 1 which may be of any suitable form and is preferably located adjacent the tempering mechanism so that an operator may remove the bits and conveniently place them upon a moving part of the tempering mechanism. As shown, the mechanism is entirely automatic in operation and comprises a generally rectangular casing or frame 2 mounted on suitable supports or legs 3.

Within this casing is suitably mounted the improved bit moving mechanism com-

prising a conveyor 4 in the form of a flat, elongated, metal strip having upstanding bit receiving members 5 spaced along the outer face of the conveyor. These bit receiving members 5 consist of punched steel 60 having slightly upturned loop portions 6 and upstanding side portions 7 adapted to receive and hold a blank, herein in the form of a cutter bit 8 in the position illustrated in Fig. 4 during the tempering process. 65 These bit receiving members are attached to the conveyor by any suitable means, herein by riveting. The conveyor is driven and guided by suitable power driving means, herein including one or more suitable power 70 sprockets 9, herein two, located at opposite ends of the casing and driven from any suitable source of power at the same angular speed, but as this forms no important part of my invention it is not shown herein, and 75 a plurality of guiding rolls or sprockets 10. The power sprockets 9 have teeth formed on their peripheries which register with apertures 9' formed in the conveyor 4 and disposed between the bit receiving members 5 80 which cooperate in the driving of the same. These driving and guiding means are suitably fixed on shafts 11 and 12, respectively, extending between the sides of the casing 2 which are journaled in suitable bearings. 85 These shafts are disposed at an angle to the horizontal so as to direct the conveyor at an inclined plane from a point adjacent the heating furnace 1 laterally and downwardly around the roll 10 adjacent the drive sprocket, 90 into a tempering tank or bath 13, herein containing water, with only the tips of the bits entering the liquid and then upwardly from that tank and over an incline around a plurality of rolls 10 and again downwardly 95 into another tempering bath or tank 14, herein containing oil, through which the tips of the bits likewise pass, then upwardly around another roll 10, the conveyor then discharging the tempered bits at this point 100 by gravity into a suitable receptacle 15 and then following a path around the drive sprocket 9 beneath the tanks 14 and 13, respectively, back to the starting point adjacent the heating furnace.

As a result of my improvement, it will be noted that all tendency to temper the entire bit and consequently produce bits having hardened shanks which the set screws grip with difficulty has been entirely eliminated,

only the tips of the bits being subjected to the tempering baths in my improved device due to the disposition of the conveyor at an angle to the bath and the consequent elimination of any tendency of a too slack or otherwise improperly adjusted conveyor to cause a flow over the bit body. Moreover, it will be noted that the bits are definitely held in position on the inclined conveyor at the same time that they are readily and automatically separable therefrom when desired.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a tempering mechanism for blanks, a tempering bath, and means disposed in an inclined position to immerse substantially the entire end of a blank in said bath.
2. In a tempering mechanism for cutter bits, a tempering bath, and cooperating immersing means supporting a bit in inclined position so that only the point is immersed in said bath.
3. In a tempering mechanism for cutter bits, a tempering bath, and immersing means supporting a bit in inclined position above said bath and automatically operative after immersion to discharge said bit.
4. In a tempering mechanism for cutter bits, a plurality of tempering baths, and means to move a series of bits above said baths in an inclined position so that only the points are immersed.
5. In a tempering mechanism for blanks, a tempering bath, and means disposed in an inclined plane to move and support the blanks in such manner as to immerse only the ends thereof in said bath.
6. In a tempering mechanism for cutter bits, a tempering bath, conveyor means for moving a series of bits above said bath, and means to guide said conveyor means in an inclined plane so that only the points of the bits are immersed in said bath.
7. In a tempering mechanism for cutter bits, a tempering bath, means to move a series of bits above said bath, and means to incline said bits so only the points of the bits are immersed in said bath.
8. In a tempering mechanism for cutter bits, a tempering bath, a conveyor having bit receiving means disposed thereon adapted to move a series of bits above said bath, and means to incline said bits so that the points only are immersed in said bath.
9. In a tempering mechanism for cutter bits, a plurality of tempering baths, means

to move a series of bits above said baths, means to incline said means so the bit points only are immersed in said baths, and means for automatically discharging said bits.

10. In a tempering mechanism for cutter bits, a tempering bath, a conveyor system having provision for carrying a series of bits with their points disposed below said conveyor, means to incline said bits so the points only are immersed in said baths, and means to discharge said bits.

11. A tempering mechanism for mining machine cutter bits comprising an inclined conveyor system having provision for carrying a bit with its point disposed below said conveyor, a bath, and means for passing said inclined conveyor over a bath in such a manner that only the point of the bit is immersed.

12. A tempering mechanism for cutter bits comprising an inclined conveyor system having provision for carrying a bit with its point disposed below the conveyor, a plurality of baths and means for passing said inclined conveyor successively over said baths in such a manner that only the point of the bit is immersed.

13. A tempering system for cutter bits comprising an inclined conveyor system having provision for carrying a bit with its point disposed below the conveyor, a water bath, an oil bath, a bit receptacle, and means for passing said bit relative to said elements in such a manner that the point only of the bit is immersed in said water and oil baths successively and that the bit is subsequently discharged into said receptacle.

14. In a tempering mechanism for blanks having projecting portions formed thereon, a tempering bath, and means disposed in an inclined position adjacent said bath for immersing only said projecting portions therein.

15. In a tempering mechanism for blanks, a tempering bath, means disposed in an inclined position to move a series of blanks adjacent said bath so that only the points are immersed, and means for holding said blanks in position on said means.

16. In a tempering mechanism for blanks, a tempering bath, means disposed in an inclined position to move a series of blanks adjacent said bath so that only the points are immersed, and means provided with up-standing blank engaging portions for holding said blanks in position on said means.

17. In a tempering mechanism for blanks, a tempering bath, means disposed in an inclined position to move a series of blanks adjacent said bath so that only the points are immersed, and means including loop portions for holding said blanks in position on said means.

18. In a tempering mechanism for cutter

bits, a tempering bath, means disposed in an inclined position to immerse substantially the entire point of the bits in said bath, and grinding and driving means for said means.

19. In a tempering mechanism for cutter bits, a tempering bath, conveyor means for moving a series of bits above said bath having apertures formed therein, and means to guide said conveyor means in an inclined plane so that only the points of the bits are immersed in said bath, said means in-

cluding sprockets cooperating with said apertures.

20. In a tempering mechanism for cutter bits, a tempering bath, conveyor means for moving a series of bits above said bath, and means including a plurality of rolls to guide said conveyor means in an inclined plane so that only the points of the bits are immersed in said bath.

In testimony whereof I affix my signature.

SVEN T. NELSON.

Certificate of Correction.

It is hereby certified that in Letters Patent No. 1,522,972, granted January 13, 1925, upon the application of Sven T. Nelson, of Michigan City, Indiana, for an improvement in "Tempering Mechanism," errors appear in the printed specification requiring correction as follows: Page 2, line 84, claim 11, for the word "than" read *that*; same page, line 90, claim 12, after the word "baths" insert a comma; page 3, line 4, claim 18, for the word "grinding" read *guiding*; and that the said Letters Patent should be read with these corrections therein that the same may conform to the record of the case in the Patent Office.

Signed and sealed this 7th day of April, A. D. 1925.

[SEAL.]

KARL FENNING,
Acting Commissioner of Patents.
